SQUEEGEE AND WRINGER MOP

Filed March 24, 1930

Harry Hertzberg INVENTOR.

BY

Martin Jacksonson ATTORNEY.

UNITED STATES PATENT OFFICE

HARRY HERTZBERG, OF BROOKLYN, NEW YORK, ASSIGNOR TO HERTZBERG PATENTS INC., OF NEW YORK, N. Y., A CORPORATION OF NEW YORK

SQUEEGEE AND WRINGER MOP

Application filed March 24, 1930. Serial No. 438,473.

This invention relates to wet mops and more particularly to that type of such mops which are intended for cleaning floors and are provided with means to wring water from the mop material.

It is the object of this invention to improve the action of a mop of this kind by providing it with a squeegee plate to collect water on the floor for absorption by the mop material in 10 a single operation.

It is another object of this invention to provide a mop of this type with means thereon to wring the water absorbed in the above described manner from the mop material without the use of separate apparatus.

It is another object of this invention to provide means on the mop head which facilitate the separation of the mop material therefrom for cleaning the same.

20 The present invention has also for its object the carrying forward the same inventive concept disclosed in my pending application for Letters Patent for "Squeegee mop", filed Sept. 5th, 1929, Ser. No. 390,609.

25 With these and other objects in view the invention also consists in certain novel features of construction, combinations of elements and arrangements of parts which will be more fully described in these specifications 30 and finally pointed out in the appended claims.

The invention is shown in the accompanying drawings which form a material part of these specifications, and in which:

35 Fig. 1 is a perspective elevation of my improved mop showing the mop cords stretched and the squeegee plate in operating position.

Fig. 2 is a side elevation of the lower end of the mop, in section on line 2—2 of Fig. 3.

40 Fig. 3 is a side elevation of Fig. 2 seen from the right side of that figure. Parts are broken out in this figure to show interior construction.

Fig. 4 is a side elevation of the mop showing squeegee plate and mop material in co-operative position.

45 Referring to the drawings, this mop consists of a mop stick 11 to the lower end of which a mop frame is fastened, which consists preferably of a metallic rod 12 bent into

a T shaped yoke. The horizontal bar of the T forms a flat loop and the vertical end portions, lying side by side close to each other, form a stem 12a which is held within an axial aperture of mop stick 11 which is preferably capped with a ferrule 13.

The mop material consists preferably of rope-like strands 20 lying side by side which are united at their lower ends by a suitable rectangular piece of canvas 22 which is doubled upon itself. The ends of the mop strands are placed between the two layers of canvas and sewed thereto by a plurality of transverse rows of stitches 23 (see Fig. 2).

Below the ends of the mop strands the two 55 layers of canvas are sewed to each other by several rows of stitches 23a so that a transverse sheath 24 is formed thereby. The mop strands extend upward along the mop stick

11 and their upper ends surround and are 60 fastened to a preferably wooden sleeve 15 which is slidably and rotatably mounted on 65 mop-stick 11. The loop 12 at the lower end of the mop carries a rectangular squeegee plate 21 of pliable material preferably rubber.

The rounded end portions of loop 12 pass through apertures in plate 21 which is of considerable thickness transversely in its middle portion and is chamfered down towards its longitudinal edges. This construction 70 makes the plate glide smoothly on a floor and avoids shattering in operation.

Between plate 21 and the upper bar 12c of the yoke an originally cylindrical piece of tubing or hose 30 is interposed and flattened 75 out longitudinally in its middle portion by pressing bars 12b and 12c towards each other.

In this manner two parallel tubes 30a and 30b are formed which extend along bar 12c on either side thereof. The hollow interior 80 of tube 30a accommodates a metallic rod 31a which is doubled upon itself at both ends of the tube at 31b so that the two parts 31c of the bar extend in opposite directions in axial alignment to each other and parallel 85 to 31a outside of tube 30a towards the mop stick 11, forming an elongated link, but the ends 31d of link 31 are spaced a distance apart. The tube 30b on the opposite side of bar 12c is occupied by a rod 32 which is of

the same length as tube 30b and together with bar 12c and bar 31a prevents lateral movement of the tubes 30a and 30b. The tubular portion 24 of the mop material is threaded first upon one bar 31c through the space between the ends 31d and then upon the other bar 31c to be supported thereon as shown in all figures of the drawings. To facilitate this attachment of the mop material to 31c these bars may be rotated on the axis of 31a in tube 30a as indicated by the dotted lines in Fig. 2.

In like manner the mop material may be removed from the holding bars 31c. The 15 mop material may be separated from the mop by moving the sleeve 15 upward and slipping it off the mop stick 11.

In the above described manner a very efficient and useful mop is produced which has 20 very few and extremely simple parts, rigidly fastened to each other with the exception of the mop material which may easily be removed from or attached to the frame. Fig. 4 illustrates the action of mopping up water 25 from a floor under assistance of the squeegee plate which when moving in the direction indicated by an arrow, pushes any water not previously absorbed by the passing mop towards the same to be absorbed thereby which 30 leaves the floor surface completely dry.

When the mop material is saturated the wringing attachment is placed in the position of Fig. 1 to wring the water from said material by turning knob 15 on mop stick 11 and 35 twisting the mop material.

The principal advantage of this mop is that the operating edge of the squeegee plate is unencumbered by the mop material as shown in Fig. 4. A further important improvement 40 is the facility with which the mop material may be removed from the mop frame particularly the fact that the squeegee plate does not have to be removed for this purpose.

Having thus described my invention what 45 I claim as new and desire to secure by Letters Patent is:—

1. A mop including a handle, a frame with a loop fixed to one end of said handle, a squeegee plate held within the loop of said 50 frame and means connected to said frame for detachably holding a sheet of mop material spread out above said plate and transversely to said handle.

2. A mop, including a mop handle, a frame 55 at one end of said handle having a pair of bars perpendicular to said handle, a squeegee plate interposed between said bars in a plane transverse to said handle, a tubular member joined to said frame and a link held by said 60 tubular member for connecting mop material to said frame.

3. A mop, including a mop handle, a frame 65 at one end of said handle having a pair of bars perpendicular to said handle, a squeegee plate interposed between said bars and having

parallel operating edges at opposite sides of said handle and a looped rod forming a link attached to said frame, the ends of said link being spaced apart in opposed relation providing an entrance opening into said link. 70

4. A mop including a mop handle, mop material, a frame at the lower end of said handle including a pair of parallel bars perpendicular to said handle and a squeegee plate interposed between said bars, a tubular member carried by said frame parallel to the bars thereof and an elongated link having a part within said tubular member connecting said mop material to said frame. 75

5. In a mop, a handle, a frame member including a yoke portion, a squeegee plate carried by said yoke portion and having working edges on opposite sides of said handle, a sleeve slidably mounted on said handle, a tubular member carried by the frame, a yoke member having one of its portions hingedly secured to said tubular member and mop material having one end gathered in folds around the handle and secured to said sleeve and having its other end secured to said hinged yoke member. 80

Signed at Brooklyn, in the county of Kings and State of New York this 20th day of March, A. D. 1930.
